UNITED STATES PATENT OFFICE.

LEE DE FOREST, OF NEW YORK, N. Y., ASSIGNOR TO DE FOREST RADIO TELEPHONE AND TELEGRAPH COMPANY, OF NEW YORK, N. Y., A CORPORATION OF DELAWARE.

SELECTIVE AUDION-AMPLIFIER.

1,397,575.

Specification of Letters Patent.

Patented Nov. 22, 1921.

Application filed April 9, 1915. Serial No. 20,173.

To all whom it may concern:

Be it known that I, LEE DE FOREST, a citizen of the United States, residing at New York, county of Bronx, State of New York, have made a certain new and useful Invention 5 in Selective Audion - Amplifiers, of which the following is a specification.

This invention relates to selective audion amplifiers.

- 10 The object of the invention is to provide an audion amplifier and suitable circuit arrangements associated therewith which will selectively amplify currents impressed thereon.
- 15 A further object of the invention is to provide an arrangement of the class referred to which will selectively amplify currents of a high frequency to a greater degree than currents of a lower frequency.
- 20 Further objects of the invention will appear more fully hereinafter.

The invention consists substantially in the construction, combination, location, and various circuit arrangements all as will be 25 more fully hereinafter set forth, as shown on the accompanying drawing and finally pointed out in the appended claims.

Referring to the drawing,—

Figure 1 is a diagrammatic view of a receiving or relay station embodying my invention.

Figs. 2 and 3 show modified circuit arrangements for accomplishing the purposes and embodying the principles of my invention.

The same part is designated by the same reference character wherever it occurs throughout the several views.

It is well known that in long distance telephonic or telegraphic circuits, especially where many miles of cable conductors are employed as distinguished from radio communications, a distortion of the telephonic or telegraph signal currents is observed, due 40 to the distributed capacity of the line wire or cable. This is particularly true of the telephone lines. The higher frequency currents are attenuated at a greater rate than those of lower frequencies, so that the 45 production of the voice at the distant receiving station becomes faulty or unintelligible. To counteract this attenuation of

the higher frequencies by the distributed capacity of the line, artificial inductance, usually in the form of Pupin "loading" 55 coils, is introduced at regular intervals along the line. This method, though effective, is an exceedingly expensive one, and offers certain additional objections.

It is among the special purposes of my 60 present invention to provide means for preventing undue attenuation of the higher frequency telephonic currents, or, in other words, means for restoring these currents to their original or nearly original amplitudes at the receiving station.

In accordance with my invention, I propose to employ a well known form of audion amplifier, such as is shown and described in my Letters Patent No. 841,387, issued to 70 me on January 15, 1907, and so associating circuit arrangements therewith that the audion will perform its amplifying function selectively; in other words, incoming currents, or currents of certain frequencies received by the audion will be amplified to a greater degree than currents of other frequencies, and especially, currents of lower frequencies. In addition, thereto, the principle of selective amplification, can be emphasized as much as is desired or necessary, so that, if desired, the normal voice currents before going in on a telephone line can first be distorted and the higher harmonics thereof made of greater amplitudes so that after 85 these latter currents are reduced in amplitude by the distributed capacity of the telephone line, the composite current will arrive at the distant receiving station in its normal or original form.

In applying my invention, the selective audion amplifier may be introduced at several intermediate points along the line so as to restore the wasted higher frequency components of the current waves, before they 95 have been completely attenuated by the distributed capacity of a long line. Thus, for example, in a telephone line extending say three thousand miles, a selective audion amplifier may be installed at ten points along 100 the line at approximately three hundred miles apart, so arranged and tuned as I shall hereinafter describe, and the telephonic or voice currents will leave each separate sta-

tion reinforced in amplitude and with a wave form similar to the original form at the first or sending station.

Referring to the drawing—

- 5 Reference character 1 designates an exhausted audion bulb of the usual and well known double plate and grid type wherein is located the usual filament F which is heated from the current source A and controlled by the variable resistance R. The grid elements or "input" electrodes G, G, are preferably arranged on either side of the filament F, and, as shown in Figs. 1 and 2, are connected in parallel. The wing, or 10 plate electrodes W, W, are also arranged on respectively opposite sides of the filament F, and at a different distance therefrom relative to the grid electrodes G, G. The incoming current to be amplified is led from the line to the primary coil S, of a transformer 15 T, preferably a step-up transformer. While I am not to be limited to the specific arrangement shown, I prefer to have the secondary coil of the transformer T wound in two parts disconnected from each other as 20 shown at O, the parts thereby possessing a large capacity relative to each other. One end of one winding of the secondary coil of the transformer T is connected directly to 25 the filament F of the audion 1, while one end of the other coil is connected to the grids G, G, of the audion 1. If desired, in the 30 transformer and grid circuit, a condenser may be inserted, as shown in dotted lines at 35 P. The plate or wing electrodes W, W, are connected through an inductance coil of a transformer V to one terminal, preferably the positive terminal of a source of current such as a battery B, the other, preferably the 40 negative, terminal of which is connected to the filament F of audion 1. The outgoing or live circuit L is connected to the secondary of the transformer V.

An oscillating circuit consisting of the 45 inductance E and capacity H is connected by one terminal to the wing or plate electrodes W, W, and by the other terminal to the grid electrodes G, G. If desired, and as shown, a capacity preferably in the form of a variable condenser C, may be inserted in this circuit. I prefer to insert a variable damping 50 resistance J in lead of this circuit to the grid electrodes. The object of this damping resistance is to reduce the amplitude of the potential surges delivered from the oscillating 55 circuit H, E, to the grid electrode, as above described.

The natural period of vibration of this 60 oscillating or "parasitic" circuit depends to a great extent upon the amount of inductance of the coil E and the amount of the capacity of the condenser H. This frequency also depends upon the constants of the audion itself, the brightness of the filament F, the applied potential from the bat-

tery B, the amount of resistance J, and the amount of resistance D connected between the grid and filament electrodes of the audion.

While I have shown the resistance J connected in the grid electrode lead of the oscillating circuit, it is obvious that it may, if desired, be connected in the oscillating circuit H, E, itself, and still perform its damping function efficiently, and therefore, I am 75 not to be limited, in the broad scope of my invention to the specific relative position thereof shown and described.

In addition to the first oscillating or "parasitic" circuit, if desired, a second similar 80 circuit comprising the elements C', J', E', H', identical with the corresponding elements of the first circuit, may be connected between the grid and plate electrodes, but the oscillating circuit E', H', should be 85 tuned to a different frequency, or natural rate of oscillation than that of the first oscillating circuit. Similarly, any number of oscillating circuits, each tuned to a different frequency, can be connected to the 90 audion.

It is not necessary, however, to connect such a "parasitic" or "reinforcing" circuit to the audion for each different frequency it is desired to amplify. I have found that 95 one such circuit, the natural fundamental frequency of which may be such as to cause it to tend to oscillate approximately 1500 times per second, will cause incoming currents having frequencies considerably higher 100 than 1500 to be amplified almost to the same degree while at the same time not permitting currents having considerably lower frequencies to be thus auto-amplified. I have found that two such "reinforcing" circuits, 105 the natural period of one of which is such as would cause the audion to deliver a sustained note of a frequency of about 1500 per second, if free to oscillate; and the natural period of the other of which is such as would cause the audion to deliver, if free to oscillate, a sustained note of about 2500 per second, will reinforce currents of all frequencies between 1200 and 3000 per second. It is 110 therefore possible to arrange a single audion with reinforcing circuits to so selectively amplify voice currents that all the higher harmonics are amplified over those of the lower or fundamental frequencies.

The principles involved in enabling an 115 audion to amplify different frequency currents unequally may be briefly stated as follows. If an oscillating or "semi-oscillating" circuit be associated with an audion in certain arrangements the audion will set 120 up, or tend to set up in such oscillating or semi-oscillating circuits, oscillating or pulsating currents which are or tend to become self-perpetuating. Such currents then rapidly build up to relatively large ampli- 130

tudes. It frequently happens, unless special means be taken to prevent it, that these oscillating or pulsating currents persist, setting up a sustained singing note in the telephone receiver connected with the audion. This of course is objectionable, and it is easy to prevent this by introducing into the pulsating current circuit, damping elements such as a high resistance which while 10 not completely annulling the tendency of such circuits to oscillate and to amplify currents possessing their natural or individual frequency, nevertheless prevent the persistent automatic oscillation of those circuits.

15 In Fig. 2 I show another circuit arrangement used in connection with an audion for amplifying currents of certain frequencies to a greater degree than other currents having lower frequencies. In this 20 form of my invention the two oscillating circuits contain inductances X' and X^2 , the capacities C' and C^2 , and the damping resistances J' and J^2 , respectively. These two circuits are connected in parallel across the 25 grid and filament electrode terminals of the audion amplifier 1. Each of these inductances are associated with an inductance Z in the "out-put" or plate electrode circuit. With this arrangement of circuits, the 30 audion would become the source of persistent oscillating currents set up in the wing or plate circuit and "reflected" back upon the grid circuit to be again amplified were it not for the presence in said circuits of 35 the damping resistances J' and J^2 . Nevertheless these circuits possess the tendency to amplify currents impressed upon the audion from the source provided the frequencies of these currents approximate those 40 of the "reflection" or reinforcing circuits.

In Fig. 3 I have shown another circuit arrangement for accomplishing the objects of my invention wherein the incoming currents are conducted to one of the grid electrodes, as G' . One of the wing or plate electrodes W' is connected to the outgoing line in the usual manner hereinbefore described. The oscillating or "reinforcing" circuits are connected to the other electrodes W^2 , G^2 of 45 the audion bulb 1. Each of the oscillating circuits contains a common inductance X associated with the coil Z in the output circuit in the manner shown and described in Fig. 2. The individual inductances E' , E^2 , E^3 , 50 etc., each in series with a capacity H' , H^2 , H^3 , etc., respectively determine the period of the reinforcing circuits, on which in this figure I have shown three. The effect of 55 these reflection circuits associated with the out-put circuit is to impart to the audion a tendency to disproportionately amplify currents having frequencies generally approximately those of the three reinforcing circuits. In this arrangement the usual 60 damping resistance J is inserted in the com-

mon path of these circuits to prevent the audion from "singing" as hereinbefore described.

While I have shown and described several circuit arrangements for accomplishing the objects and purposes of my invention, it will be understood that my invention, in its broad scope is not to be limited thereto, as various other arrangements will occur to those skilled in the art for accomplishing the same results without departing from the scope of my invention as defined in the claims.

What I claim as new and useful and of my own invention, and desire to secure by Letters Patent, is,—

1. An amplifier, including an input and an output circuit, and a plurality of oscillating circuits associated therewith to selectively amplify the current of certain frequencies in the input circuit.
2. An amplifier, including an input and an output circuit, circuit connections therefor, and means associated therewith to selectively amplify the current of certain frequencies in the input circuit.
3. An amplifier, circuit connections therefor including input and output circuits, and means associated therewith to amplify currents of certain frequencies impressed on the input circuit to a greater degree than other frequencies impressed on the input circuit.
4. An amplifier, an input and an output circuit therefor and a plurality of oscillating circuits associated therewith to amplify impressed currents of certain input frequencies to a greater degree than impressed currents of other frequencies.
5. An amplifier, circuit connections therefor including input and output circuits, and means associated therewith to amplify currents of certain frequencies impressed on the input circuit to a greater degree than currents of lower frequencies impressed on the input circuit.
6. An amplifier, an input and an output circuit therefor and a plurality of oscillating circuits associated therewith to amplify impressed currents of certain input frequencies to a greater degree than impressed currents of lower frequencies.
7. In an audion repeater system, an audion comprising a hot electrode and cold electrodes, an input circuit associated with one cold electrode and an output circuit associated with the other cold electrode, and a plurality of oscillating circuits connecting said cold electrodes.
8. In an audion repeater system, an audion comprising a hot electrode and two sets of cold electrodes, input and output circuits associated with said audion, and a plurality of oscillating circuits connected between said cold electrodes.
9. In an audion repeater system, an audion

4

comprising a hot electrode and cold electrodes, an input circuit associated with one cold electrode and an output circuit associated with the other cold electrode, and a plurality of oscillating circuits connecting said cold electrodes, and means for damping each of said oscillating circuits.

10. In an audion repeater system, an audion comprising a hot electrode and two sets 10 of cold electrodes, input and output circuits associated with said audion, and a plurality of oscillating circuits connected between said cold electrodes and means for damping each of said oscillating circuits.

15. 11. In an audion repeater system, an audion comprising a hot electrode and cold

electrodes, an input circuit associated with one cold electrode and an output circuit associated with the other cold electrode and a plurality of oscillating circuits connecting 20 said cold electrodes, and a variable resistance inserted in each of said oscillating circuits.

12. In an audion repeater system, an audion comprising a hot electrode and two sets of cold electrodes, input and output circuits 25 associated with said audion, and a plurality of oscillating circuits connected between said cold electrodes, and a variable resistance inserted in each of said oscillating circuits.

In testimony whereof I have hereunto set 30
my hand this 7th day of April, A. D. 1915,
LEE DE FOREST.
